1885.

Mar. 768

Samuel D. Vose, of Albany, N.Y.
Letters Patent No. 768. Dated March 4th 1856.

The schedule referred to in these Letters Patent, and making part of the same.

To all whom it may concern,

Be it known that I, Sam'l D. Vose, of Albany, County of Albany, and State of New York, have invented or produced a new and useful design for a parlor stove, and I do hereby declare that the following is a full and exact description, reference being had to the annexed drawings affixed to and making part of this specification.

The nature of my invention will not admit of its being easily described in words: reference is therefore made to the drawings in which the figures are respectively designated by the following names. Top: Bottom: End: Front: Upr: Leg: -

Two ends and two fronts are necessary to form the body of the stove, but they are represented by the single figures marked end and front respectively.

When these several figures or plates are set up together, they form an ornamental stove. The combination of the moldings and ornaments on these configurated plates, is what I claim as my invention. I do not claim any separate figure or ornament.

What I claim as my invention, and desire to secure by Letters Patent, is the combination of the various ornaments and moldings on the several plates, as shown in the drawings, the whole forming an ornamental design for a parlor stove.
